NONSPILLABLE DRINKING UNIT

Edwin J. Nicorvo, South Amboy, N. J.

Application April 15, 1949, Serial No. 87,673

1 Claim. (Cl. 65—13)

1

This invention relates to drinking units and is directed to novel non-spillable drinking units. The drinking units of this invention are especially designed for children's use, may be easily and readily produced at relatively low cost, may be easily assembled and taken apart and are of rugged construction.

The various objects and advantages of the invention will be apparent from the following description and drawings, wherein:

Fig. 1 is a cross sectional view taken vertically through a novel drinking unit embodying the invention, and on line 1—1 of Fig. 2.

Fig. 2 is a cross sectional view taken on 2—2 of Fig. 1.

Fig. 3 is a fragmentary view taken on line 3—3 of Fig. 1.

According to this invention, the novel drinking unit comprises a drinking container which may be a drinking glass, tumbler or cup 10 having a base 11 integral with a usually hollow cylindrical or frusto-conical body 12 open at its normally upper end. The body 12 has a narrow supporting bead 13 integral therewith and extending inwardly from the inner surface thereof. The bead 13 extends around the entire inner circumference of said body 12 in a plane at right angles to the vertical axis body of 12 and is located near, but appreciably below the upper or open end of body 12. The body 12 has a narrow, elongated opening 14 therein located above the bead 13, and a plurality of projections 15 spaced from each other and integral with and extending inwardly from the interior surface thereof. The projections 15 are located in a plane at right angles to the vertical axis of body 12, and each of said projections is spaced from the bead 13.

The container as heretofore described may be composed of any desirable material, but it is preferable that it be composed of a so-called plastic material, and of that type which has high impact strength and is shatter-proof. For these purposes, I prefer that it be composed of polyethylene.

A cover plate may be demountably coupled with the container 10 and comprises a circular disc 16 whose diameter is the same as or just slightly less than the inside diameter of the ring of the inside wall of body 12 between the bead 13 and projections 15, and whose thickness is the same as or just slightly less than the distance between projections 15 and bead 13. The cover plate 16 may have an upstanding eye 17 integral therewith and carrying a lift ring 18. The cover plate 16 also may be composed of

2

plastic material, such as cellulose acetate and is rigid, yet flexible and resilient for coupling and uncoupling as hereinafter described.

The cover plate 16 has a discharge opening 19 therethrough and one side of the opening is located near but within the circumferential periphery of cover 16. A swingable closure or slide valve 21 of cellulose acetate is mounted on cover 16 to lie over the opening 19 and provide a liquid-tight closure. The closure 21 is pivotally secured to the cover plate 16 by a plastic rivet 22 composed of "nylon" and extending through closure 21 at one end thereof and through cover 16. Secured to the closure 21 is a plastic split pin 23 of "nylon," having upstanding ends which may be flexed toward each other. The foregoing sub-assembly may be demountably secured to the container by dropping it upon the projections 15, applying pressure to the center of plate 16 to flex it, whereupon its circular periphery will snap into the space between said projections 15 and bead 13. Pressure is released and the sub-assembly automatically latches itself in that space, with the cover plate 16 bearing against the inner wall of body 12, the shoulder of the bead 13 and the projections 15 to provide a liquid-tight seal therebetween.

Then an actuator 25, in the nature of a flat rod 26 having an opening in the free end thereof and having its other end integral with a short handle 27, is coupled therewith. The rod 26, having a resilient member such as a coiled spring 28 wound therearound, is inserted through opening 14 and the split pin 23 is inserted through the opening in the end of rod 26 to frictionally latch the actuator 25 to the closure 16. With this accomplished, the spring 28 bearing against the outer wall of body 10 and the upper end of gripper 27 exerts a force outwardly on actuator 25 to maintain the valve 21 in operative or closed position.

With this assembly embodying the invention, the liquid, such as milk, water or etc., which may already have been poured into the container 10, cannot flow out of said container when the assembly is tipped on to its side, either accidentally or on purpose by the child. Yet if the child desires to drink therefrom, he grasps the assembly at its upper end and presses against the handle 27 of actuator 25 to move the rod 26 against the action of the spring 28, to swing the closure 21 about the pivot 22 to the dotted line position shown in Fig. 2. Now the liquid is free to flow through opening 19.

If while the child is drinking, the unit drops

out of his hand, the spring 28 acting upon the rod 26 automatically returns the closure 21 to closed position as the unit drops to the floor or table. No liquid will spill therefrom because the device is again a liquid-tight compartment.

While this invention has been described in detail, it is not to be limited thereby, because various changes and modifications may be made within the spirit thereof.

I claim:

A drinking unit comprising a container having an open mouth at its normally upper end, a cover demountably mounted in said upper end and disposed below the upper periphery of said container and having a discharge opening therethrough, the upper end of said container having an opening therethrough located above said cover, a valve for said discharge opening and disposed below the upper extremity of said container, said valve pivotally mounted on said cover, a rod extending through said opening in said container, one end of said rod connected to said valve, a gripper connected to the other end of said rod and located outwardly beyond

the outer surface of said container, a spring associated with said rod and normally acting upon said rod to maintain said valve in closed position, said rod being actuatable against the action of said spring by the application of a force to said gripper to swing said valve to open position and being disposed below the upper end of said container.
